(57) **CLAIM**

The ornamental design for a display screen or portion thereof with animated graphical user interface for risk simulator, as shown and described.

DESCRIPTION

FIG. 1 is a front view of a display screen or portion thereof with an animated graphical user interface for a risk simulator showing a first image according to an embodiment of our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof;

FIG. 11 is a front view of an eleventh image thereof;

FIG. 12 is a front view of a twelfth image thereof;

FIG. 13 is a front view of a thirteenth image thereof;

FIG. 14 is a front view of a fourteenth image thereof;

FIG. 15 is a front view of a fifteenth image thereof;

FIG. 16 is a front view of a display screen or portion thereof with an animated graphical user interface for a risk simulator showing a first image according to an embodiment of our new design;

FIG. 17 is a front view of a second image thereof;

FIG. 18 is a front view of a third image thereof;

FIG. 19 is a front view of a fourth image thereof;

FIG. 20 is a front view of a fifth image thereof;
